UNITED STATES PATENT OFFICE

2,315,991

ELECTRIC CIRCUIT BREAKER

Carl Thumim, Yeadon, Pa., assignor to General
Electric Company, a corporation of New York

Application June 28, 1940, Serial No. 343,002

14 Claims. (Cl. 200—148)

My invention relates to electric circuit breakers and operating systems therefor and more particularly to operating systems for effecting high-speed operation of circuit breakers of the fluid-blast type. Specifically, my invention is an improvement on the circuit breaker operating system disclosed and claimed in the copending joint application of myself, E. J. Frank and A. C. Boisseau, Serial No. 317,564, filed February 6, 1940, and assigned to the same assignee as the present application.

In an effort to eliminate the fire hazard, circuit breakers have been designed which do not utilize oil or other inflammable liquid for arc-extinguishing purposes but instead employ a blast of fluid, preferably air or other gas, to extinguish the arc formed both when the circuit is broken between the relatively movable contacts of the circuit breaker and also during the closing operation of the circuit breaker to prevent the formation of any arc at that time. Such fluid-blast circuit breakers provide numerous operating and structural advantages for many applications but the problem of providing a suitable control or operating system, particularly when high-speed operation is desired, furnishes considerable difficulty.

The value of any circuit breaker lies in its ability to interrupt the circuit at the proper time and in the proper manner. Therefore, without a satisfactory control or operating system, the value of a circuit breaker, however efficient and reliable, is largely lost for, if control of the circuit breaker in the manner intended is not obtained, many undesirable conditions may result.

Since a gas-blast circuit breaker depends upon a blast of gas, such as air, for arc-extinguishing purposes, it is essential that such blast of air occurs simultaneously with or prior to the separation of the contacts. In some of the prior-art arrangements, it was possible for the contacts to separate without the existence of the necessary arc-extinguishing blast, and often considerable damage resulted not only to the circuit breaker, itself, but to associated apparatus. It would be desirable to provide a control and operating system for a gas-blast circuit breaker in which separation of the contacts cannot ordinarily take place until a blast of gas, such as air, for arc-extinguishing purposes exists at the contacts when an arc is drawn therebetween.

Ordinarily, it is desirable to be able to open the circuit breaker contacts for interrupting the circuit in as short a time as possible after the condition which initiates the opening movement

occurs. This is no less true of gas-blast circuit breakers than of any other type and, accordingly, it is necessary that high-speed valves for controlling the gas blast be provided. It would be desirable to provide valves for gas-blast circuit breakers which may be operated either manually or automatically with a relatively small force and which not only operate with very high speed but which are positive and efficient in their action.

Accordingly, it is an object of my invention to provide a new and improved operating system for a fluid-blast circuit breaker wherein rapid, positive, and efficient high-speed interruption may be obtained combined with reliability, economy, and low first cost.

It is another object of my invention to provide a new and improved operating and control system for a circuit breaker of the gas-blast type in which a blast of gas, such as air, is insured adjacent the contacts prior to any separation between such contacts of the circuit breaker.

It is a further object of my invention to provide a new and improved blast valve for the operating system of a gas-blast circuit breaker.

Further objects and advantages of my invention will become apparent as the following description proceeds and the features of novelty which characterize my invention will be pointed out with particularity in the claims annexed to and forming a part of this specification.

For a better understanding of my invention, reference may be had to the accompanying drawings in which Fig. 1 is a schematic diagram partly in section of an operating and control system for a gas-blast circuit breaker embodying my invention, Fig. 2 is a sectional view of a solenoid-operated valve shown schematically in Fig. 1, Fig. 3 is a sectional view of the blast valve and associated apparatus shown schematically in Fig. 1, Fig. 4 is a sectional view of a pneumatically controlled tripping means and interlock therefor shown schematically in Fig. 1, and Fig. 5 is a sectional view taken on line 5—5 of Fig. 4.

Although my invention is applicable to polyphase or single-phase circuit breakers, I have illustrated my invention schematically in Fig. 1 as applied to a polyphase circuit breaker 10, only the structure associated with one set of contacts for one pole 10a of the circuit breaker being shown since the other poles of the circuit breaker are identical. Where I have illustrated any operating mechanism for the various phases or poles which are identical for each phase or pole, such parts are hereinafter characterized by the same reference numerals with the subscript *a*, *b*, or *c*.

depending upon the particular phase or pole of the circuit breaker. Circuit breaker 10 is illustrated as of the cross gas-blast type and the pole 10a thereof is illustrated as comprising a stationary contact 11a and a movable contact 12a arranged to be operated so as to draw an arc in arc chute 13a. Contacts 11a and 12a are arranged to be connected with suitable line terminals, not shown. The fixed contact 11a is provided with spring-pressed contact fingers 14a and longer arcing contact fingers 14'a, while movable contact 12a is provided with an arcing tip 12'a so that, when the contacts separate, an arc occurs between arcing tips 14'a and 12'a. Immediately after separation of the contacts, one terminal of the arc is transferred by a blast of fluid, such as air, flowing in conduit 15 from contact fingers 14'a to the contact 14'a which is provided with a tip of arc-resistant metal. The fluid blast from conduit 15 upon opening of the circuit breaker drives the arc into the arc chute 13a against the edges of a plurality of partitions 16a in the arc chute, which partitions are transverse to the arc gap and the ends of which extend close to the path of movement of the arcing tip 12'a of movable contact 12a. The circuit breaker 10, only pole 10a of which is shown, is illustrated by way of example in order to describe my new and improved operating and control system. This circuit breaker, briefly described heretofore, is not my invention but is described and claimed in the joint application of David C. Prince, William K. Rankin, and Wilfred F. Skeats, Serial No. 303,126, filed November 6, 1939, now Patent No. 2,284,842, issued June 21, 1942, and assigned to the same assignee as the present application.

Each of the movable contacts of the various poles or phases of circuit breaker 10, such as 12a which alone is illustrated, is connected to individual operating rods 17a, 17b, and 17c, respectively. These individual operating rods 17a, 17b, and 17c are respectively connected to one end of suitable levers 18a, 18b, and 18c, each having the other ends thereof provided respectively with cross heads 19a, 19b, and 19c arranged to slide in cross-head guides 20a, 20b, and 20c. Suitable buffers 21a, 21b, and 21c, respectively are provided for each of the links 18a, 18b, and 18c to cushion the closing movement of the operating mechanism and associated circuit breaker 10. Each of the links 18a, 18b, and 18c has an intermediate point thereon pivotally connected to one end of bell cranks 22, 23, and 24, respectively, which, in turn, are pivotally mounted on fixed supports 25, 26, and 27. In order that the movable contacts 12 associated with all of the poles of circuit breaker 10 are simultaneously actuated, bell cranks 22, 23, and 24 are interconnected by a horizontally reciprocating operating rod 28.

Any suitable means may be provided for producing relative movement between the contacts 11 and 12 of circuit breaker 10. In Fig. 1, I have illustrated energy-storage means comprising opening spring 29 and balancing spring 30 for supplying the force required to produce uniform high-speed opening of circuit breaker 10. Opening spring 29 is arranged to operate rod 31 which engages with roller 32 attached to an extension 24' of bell crank 24. Similarly, balancing spring 30 is connected to an extension 24'' of bell crank 24. When these springs are charged as shown in Fig. 1, they tend to cause clockwise rotation of bell crank 24 and, consequently, also of bell cranks 22 and 23 which are connected together through

horizontally reciprocating operating rod 28 which moves toward the right.

In order to close the contacts of circuit breaker 10 as well as to charge the energy-storage means comprising opening spring 29 and balancing spring 30, I provide a fluid motor 33 comprising a cylinder 34 in which is reciprocally mounted a piston 35 operatively connected to a force-transmitting rod 36 arranged to engage with a trip-free thrust-transmitting linkage generally indicated at 37. This thrust-transmitting linkage 37 has one end thereof connected to the bell crank 23 so as to cause movement of rod 28 and bell cranks 22 and 24 to close the respective contacts 11 and 12 of circuit breaker 10.

The fluid motor 33 is shown in Fig. 1 at the instant when circuit breaker 10 has just been completely closed. Since this fluid motor 33 is used only to close circuit breaker 10 and charge opening springs 29 and 30, it is desirable to provide suitable means for returning piston 35 to its initial position at the left-hand end of cylinder 34 after the closing operation is completed. Accordingly, I have shown a suitable return spring 38 mounted in a housing 39 supported by cylinder 34. Suitable ports 40 in housing 39 allow air in cylinder 34 to the right of piston 35 to escape when circuit breaker 10 is being closed.

The trip-free thrust-transmitting structure generally indicated at 37 can be of any suitable design, the one shown by way of example comprising a main toggle 41-42 including a roller 43 which coacts with the torque-transmitting rod 36 associated with piston 35. The toggle link 41 is pivotally connected at one end to a lever 44 supported on a fixed pivot 43. The toggle link 42, on the other hand, is connected at 46 to one end of a lever 47 supported on a fixed pivot 48. The other end of lever 47 is connected through link 49 to bell crank 23. The pivot 50 of the toggle link 41 is normally held fixed by a suitable tripping means including an extension 44' on lever 44 supporting a roller 51 which coacts with tripping latch 52 pivotally mounted at 52'. When the toggle 41-42 is straightened at its knee joint 53 by force-transmitting rod 36, the lever 47 is rotated about its fixed pivot 48 in a clockwise direction to cause rod 28 to move toward the left to assume the position shown in Fig. 1 when the circuit breaker is closed. When the latch 52 is moved out of restraining engagement with respect to roller 51, lever 44 is free to pivot in a counterclockwise direction. The toggle 41-42 is then no longer in thrust-transmitting position and is free to collapse, permitting movement towards the right of rod 28 under the bias of the energy-storage means comprising opening spring 29 and balancing spring 30.

In Fig. 1, the trip-free thrust-transmitting linkage 37 is illustrated in a restraining or closed position with respect to rod 28. In this position, the knee joint 53 of toggle 41-42 is overset and engages a stop member 54. The linkage is, thereby, effectively locked in this position with respect to any opening thrust tending to move rod 28 toward the right as long as the pivot 50 of toggle link 41 is held fixed by the above-described tripping means. When latch 52 of the tripping means no longer restrains link 44 and, hence, also pivot 50, the former rotates in a counterclockwise direction under the influence of the reacting forces tending to cause opening movement of horizontally reciprocating rod 28. When the toggle 41-42 has collapsed and the lever 47 is rotated in a counterclockwise direc-

tion, opening of circuit breaker 10 results through upward movement of operating rods 17a, 17b, and 17c respectively.

Because of the high opening speed of circuit breaker 10, it is desirable to provide cushioning means for retarding the opening movement so as to prevent any damage to the moving parts thereof. Accordingly, I have shown a suitable dashpot 55 connected to a pivotally mounted link 56 having a roller 57 at one end thereof which is arranged to engage with a suitable cam surface 58 provided on bell crank 22. The dashpot 55 and cam surface 58 may be so designed that any desired opening characteristic is obtained. For example, it may be desirable to so design cam surface 58 as to provide an arrangement similar to that disclosed and claimed in United States Letters Patent 1,904,539, granted April 18, 1933, upon an application of Sigwart Ruppel.

In order to operate fluid motor 33 and to provide a blast of gas, such as air, in the arc chutes 13 adjacent contacts 11 and 12 of circuit breaker 10, I provide a source 59 of gas under pressure. Fluid motor 33 is connected to source 59 of gas under pressure through conduit 60, solenoid-operated closing valve 61, and conduit 62. The cross gas blast for arc-extinguishing purposes in arc chutes 13 is also obtained from source 59 through conduit 63, blast valve 64, and conduit 15. It will be understood by those skilled in the art that a single blast valve 64 controls the flow of gas to all the poles of the circuit breaker 10 including pole 10a, and additional conduits 15, not shown, would be provided for the other poles or phases of circuit breaker 10.

Solenoid-operated closing valve 61, shown schematically in Fig. 1, is disclosed in detail in Fig. 2 as a valve of the balanced pressure type similar in some respects to the valve disclosed and claimed in United States Letters Patent 1,912,024, granted May 30, 1933, upon an application of Werner Uebermuth and assigned to the assignee of the present application. Solenoid-operated closing valve 61 is a high-speed valve with high flow efficiency so constructed and arranged as to operate in any position and comprises a valve body 65 in which is reciprocally mounted a piston-operated valve member 66 arranged to cooperate with an annular valve seat 67. Valve member 66 is suitably guided in its reciprocal movement by a plurality of ribs 65' formed integrally with valve body 65. A piston 68 mounted in a cylinder 69 formed in valve body 65 is operatively connected to valve member 66. An additional guide means comprising fluted member 70 is provided for solenoid-operated closing valve 61 which cooperates with a cylindrical surface 71 formed in valve body 65. A plurality of openings 72 are provided in valve body 65 so that, when valve member 66 is in the closed position shown in Fig. 2 in engagement with annular valve seat 67, cylinder 34 of fluid motor 33 is vented to atmosphere through conduit 60 and openings 72 whereby piston return spring 38 may readily return piston 35 of fluid motor 33 to its initial position at the left-hand end of cylinder 34 of Fig. 1.

When valve member 66 is moved away from annular seat 67 so as to provide a direct passage between conduits 60 and 62, valve member 66 cooperates with cylindrical surface 71, thereby to prevent the escape of any gas or air to the atmosphere through openings 72. The areas of piston 68 and valve member 66 are proportioned in such a manner that the forces due to fluid

pressure tend to keep the valve member 66 tightly against annular seat 67 under normal conditions, as shown in Fig. 2. Under special conditions, when there is no fluid pressure in source 59, as at the start of filling thereof, a suitable light spring 73, is provided to hold the valve closed.

To obtain maximum opening speed of solenoid-operated valve 61, it is desirable to minimize the clearance volume in cylinder 69 below piston 68 so that gas under pressure contained therein may be evacuated in a short interval of time as will be described hereinafter. A small passage 75 is provided through valve member 66 and piston 68 to interconnect cylinder 69 with the pressure source 59 through conduit 62, thereby to balance the forces due to gas pressures under steady state conditions which tend to cause movement of valve member 66 whereupon substantially the only force tending to hold valve member 66 against seat 67 is spring member 73.

In order to open solenoid-operated closing valve 61 so as to interconnect conduits 60 and 62, a pilot valve 76 of relatively large diameter is provided to release the pressure in cylinder 69 below piston 68 rapidly, thereby unbalancing the forces acting on the piston-operated valve member by reducing the force acting on piston 68 substantially to zero so that the downward force on valve member 66 is sufficient to cause valve member 66 to snap open and close off the openings 72 by the tight fit between cylinder 66 and cylindrical surface 71. Since fluid can pass through pilot valve 76 considerably faster than through opening 75 which is relatively small, no pressure can build up below piston 68 and valve member 66 will remain open until pilot valve 76 is closed.

It will be understood by those skilled in the art that the operation of pilot valve 76 requires considerably less force than would be required to move valve member 66 directly. Pilot valve 76 is normally held in closed position by spring means 77 acting through lever 78 pivoted at 79. In order to open pilot valve 76 and, consequently, to open closing valve 61, a solenoid 80 is provided to overbalance the spring means 77 which normally holds pilot valve 76 in the closed position. Thereupon pilot valve 76 is immediately caused to open by the force due to the relatively high air or gas pressure contained in cylinder 69 below piston 68. Upon deenergization of solenoid 80, spring means 77 closes pilot valve 76 and, as soon as sufficient gas has passed through small opening 75 to balance the forces due to gas pressures acting on the piston 68 and valve member 66, spring means 73 causes valve member 66 to engage valve seat 67 and interrupt the flow of gas from conduit 62 to conduit 60. Since the volume of cylinder 69 below piston 68 is very small the pressures are balanced in a short interval of time to cause rapid closing of valve member 66. Solenoid 80 may be energized from any suitable source of electrical energy when it is desired to close circuit breaker 10. It will be understood by those skilled in the art that the above-described solenoid-operated valve operates at very high speed and has a high flow efficiency.

The cross gas blast for arc-extinguishing purposes in the arc chutes 13 of circuit breaker 10 is also obtained from source 59 through blast valve 64 as mentioned above. This blast valve 64 and associated apparatus is only schematically shown in Fig. 1 in the interest of clearness and simplicity in the drawings, but the details there-

of are shown in Fig. 3. Referring now to Fig. 3, I have illustrated blast valve 64 as comprising a streamlined valve member 81 which allows fluid pressure from source 59 and conduit 63 to pass to conduit 15 with maximum flow efficiency. Valve member 81 cooperates with a replaceable valve seat 81' which is mounted in a casing 82 enclosing a cylinder 83 within which piston 84, operatively connected to valve member 81 through connecting rod 85, reciprocates. Connecting rod 85 is arranged to cooperate with a valve guide 86 to guide the opening and closing movements of valve member 81. A spring member 87 placed between valve guide 86 and piston 84 normally tends to hold valve member 81 in a closed position against valve seat 81'. Since blast valve 64 operates with high speed, suitable cushioning means are necessary and, in Fig. 3, I have disclosed a metallic striking plate 88 behind which is mounted a suitable buffer 89 to cushion and limit the opening movement of valve 81.

The area of piston 84 is larger than that of valve member 81 so that, if gas under the same pressure as that acting on valve member 66 were admitted to cylinder 83 below piston 84, valve member 81 would be moved away from its seat 81' and thus interconnect source 59 and conduit 15. Accordingly, I provide a pilot-operated balanced pressure valve 90 comprising a piston-operated valve member substantially identical with the piston-operated valve member of solenoid-operated closing valve 61 illustrated in Fig. 2 and described in detail above for controlling the application of a force due to gas pressure entering cylinder 83 below piston 84. When balanced pressure valve 90 is opened, fluid from source 59 flows through the relatively large filling passage 91 to act on the lower side of piston 84, thereby overcoming the force due to the gas pressure acting on valve member 81 and the force exerted by spring 87 so as to cause valve member 81 to snap open against striking plate 88. The volume of cylinder 83 below piston 84 when valve member 81 engages seat 81' is maintained at an absolute minimum so that gas pressure from passage 91 may become effective immediately when balanced pressure valve 90 is opened whereby very high-speed opening of valve member 81 is obtained.

Since the piston-operated valve member of balanced pressure valve 90 is substantially identical with the piston-operated valve member of closing valve 61 illustrated in Fig. 2, no further description thereof will be included here. However, the corresponding parts of the balanced pressure valves of Figs. 2 and 3 are designated by the same reference numerals, those in Fig. 3 being marked with a prime.

It will be observed by those skilled in the art that, when pilot valve 76' is opened, balanced pressure valve 90 is actuated which, in turn, acts as a pilot valve for the main piston-operated valve including valve member 81. Thus, a relatively small force for opening pilot valve 76' causes opening of valve member 81 of blast valve 64.

Pilot valve 76' is normally held in the closed position by spring 92 acting through lever 93 pivotally mounted at 94. A solenoid 95 is provided for overcoming the effect of spring 92 and allowing pilot valve 76' to open with the consequent opening of blast valve 64. Solenoid 95 is connected to lever 96 also pivotally mounted at 94 and provided with a suitable pin 97 arranged to engage with an extension 93' of lever 93 so that, when solenoid 95 is energized, levers 96 and 93

are rotated in a counterclockwise direction and pilot valve 76' is opened. A suitable spring 98 is provided to move lever 96 to the position shown when solenoid 95 is unenergized. It will be understood by those skilled in the art that solenoid 95 will be energized in response to predetermined abnormal electrical conditions which require tripping of circuit breaker 10.

As will be described in detail hereinafter, pilot valve 76' is also mechanically operable in response to the position of the contacts of circuit breaker 10 so as to provide a timed closing gas blast as well as to time the opening arc-extinguishing gas blast and, accordingly, a lever 99 is provided pivotally mounted at 94 including a roller 100 arranged to engage with an extension 93'' on lever 93. A suitable operating rod 101 connected to lever 99 is arranged to cause counterclockwise rotation thereof as well as of lever 93 to open pilot valve 76' through the interaction of roller 100 with extension 93'' of lever 93. Under these conditions, spring 98 prevents lever 96 from rotating.

Occasionally, it is desirable to control the circuit breaker manually and, to this end, pilot valve 76' may be operated by a manual operating force applied to cable 102 attached to lever 96.

In order to prevent damage to the circuit breaker and associated apparatus, it is essential that a blast of gas be provided adjacent the separating contacts simultaneously with the opening movement of the circuit breaker or preferably prior to such opening movement. I have provided a pneumatic tripping arrangement wherein tripping of circuit breaker 10 and opening movement thereof cannot occur until blast valve 64 is at least partially open and the condition of the fluid pressure source is such as to allow satisfactory interruption of the circuit.

It will be observed from Fig. 1 that circuit breaker 10 cannot be opened unless latch 52 is rotated so as to release lever 44. Accordingly, I have provided a pneumatic arrangement generally indicated at 103 for rotating latch 52 so that circuit breaker 10 may open only after blast valve 64 is open. This pneumatic arrangement 103 comprises a valve 104, conduit 105, tripping valve 106, conduit 105', and pneumatic tripping means generally indicated at 107 and illustrated in detail in Figs. 4 and 5.

Whenever opening of circuit breaker 10 is initiated either manually through cable 102 or electrically upon energization of solenoid 95, lever 96 is caused to rotate in a counterclockwise direction about pivot 94 so as to open pilot valve 76' and, consequently, also the main piston-operated blast valve including valve member 81. Valve 104 is provided in order to insure that blast valve 64 is at least partially open before circuit breaker 10 is tripped. This valve 104 is mounted on the lower end of piston 84 of blast valve 64 and closes the end of conduit 105 when valve member 81 is in the position shown in Figs. 1 and 3. However, when piston 84 has traveled a very short distance to move valve member 81 away from cooperating valve seat 81', valve 104 is withdrawn from the end of conduit 105 so that fluid under pressure may enter therein.

Tripping valve 106 is illustrated as comprising reciprocally mounted plunger 108 pivotally connected to lever 96 at 109 so that, whenever the latter is rotated to open blast valve 64, tripping valve 106 is also opened to interconnect conduits 105 and 105'. Tripping valve 106 is provided with an opening 110 through which conduit 105' may

be vented to atmosphere when valve 106 is closed, as shown in Figs. 1 and 3.

As soon as valve 104 is opened, insuring opening of blast valve 64, and with valve 106 having been previously opened, fluid under pressure is admitted to tripping means 107 shown in detail in Fig. 4. This tripping means comprises a housing 111 including a cylinder 112 within which is reciprocatingly mounted a piston 113 operatively connected to a tripping plunger 114 provided with spring means 115 opposing the force due to the fluid pressure admitted through conduit 105' and acting on piston 113. Preferably, cylinder 112, which may comprise an impregnated bushing so as to require no further lubrication, is designed to have as small a volume as possible to increase the speed of operation of tripping plunger 114 when fluid pressure is admitted thereto. The end of tripping plunger 114 is arranged to engage with tripping finger 116 mounted on the same shaft 52' as latch 52 so as to cause rotation of latch 52 and release of the trip-free mechanism 37, whereupon circuit breaker 10 may open at high speed by virtue of the energy supplied by opening spring 29 and balancing spring 30.

It would be desirable to prevent tripping of circuit breaker 10 if, for any reason, the pressure in source 59 were below a predetermined value so that such tripping would be unsafe. Accordingly, I have provided an interference interlock, generally indicated at 117 in Fig. 1 and shown in detail in Fig. 5, which prevents movement of tripping finger 116 and, consequently, prevents opening of circuit breaker 10. This interference interlock 117 comprises a cylinder 118 connected through a suitable conduit 119 to fluid pressure source 59. A suitable piston 120 is arranged to reciprocate in cylinder 118. This piston is connected to rod 121, having an enlarged portion 121' at the other end thereof, which is slideable in a cooperating guide 122. A suitable spring means 123 is provided acting on the enlarged portion 121' of rod 121 to oppose the force due to fluid pressure in cylinder 118. Whenever the fluid pressure in source 59 is above a predetermined minimum amount, piston 120 is moved sufficiently far to the right, as indicated in Fig. 5, against the force of spring means 123 so that the rod 121 is adjacent tripping finger 112, allowing free movement thereof. If, for any reason, however, the pressure in source 59 should fall below this predetermined amount, spring means 123 will cause the enlarged portion 121' of rod 121 to move to the left so as to interfere with free movement of tripping finger 116 and to prevent rotation thereof and consequent tripping of circuit breaker 10. Adjustable means 124 are provided to vary the tension of spring 123 and thereby adjust the predetermined minimum pressure below which interlock 117 becomes effective.

It may be desirable to remove the electrical control of circuit breaker 10 so that neither closing nor opening thereof can be accomplished when the pressure of source 59 is inadequate for proper circuit interruption. To this end, I may provide a low-pressure switch, not shown, similar to that disclosed and claimed in my copending joint application, Serial No. 317,564, referred to above which will render all electrical controls of circuit breaker 10 ineffective when the pressure of source 59 falls to a predetermined value.

Mechanical operation of pilot valve 76' in response to the position of the movable contacts 12 of circuit breaker 10 to provide a blast of air or gas during the closing movement of the circuit breaker as well as to time the opening arc-extin-

guishing gas blast is obtained by means of a cam 125 pivotally mounted on fixed support 27 and rotatable with bell crank 24. This cam 125 is provided with a suitable cam surface to engage roller 126 and cause movement of operating rods 101' and 101 when opening of circuit breaker 10 is initiated either manually through cable 102 or electrically by means of solenoid 95. Whenever pilot valve 76' is opened, resulting in the opening of blast valve 64 and release of the trip free thrust-transmitting mechanism 37 there occurs a clockwise rotation of bell cranks 22, 23, and 24 as well as of cam 125. Pilot valve 76' and, consequently, blast valve 64 are held open by cam 125 for a predetermined time dependent upon the shape of the cam surface provided thereon which engages with roller 126 and acts on pilot valve 76' through operating rods 101' and 101 and the length of the opening gas blast is thereby controlled.

When closing of circuit breaker 10 is initiated through energization of solenoid 80, a counter-clockwise rotation of bell cranks 22, 23, and 24 and cam 125 results. A suitable cam surface provided on cam 125 will cause opening of pilot valve 76' through operating rods 101' and 101 so as to provide a closing blast of fluid adjacent the approaching contacts of circuit breaker 10 at a predetermined point in the closing stroke thereof.

The operation of my improved control and operating mechanism will now be described briefly with reference to Fig. 1 which illustrates the apparatus at the instant the circuit breaker 10 has been closed and before piston 35 of fluid motor 33 has been returned to its initial position by spring means 38. If the pressure in source 59 is sufficiently high so that operation of circuit breaker 10 may safely be accomplished, the interlock 117, schematically shown in Fig. 1 and shown in detail in Fig. 5, does not interfere with the free movement of trip finger 116. If solenoid 95 is energized in response to an abnormal condition on the system which circuit breaker 10 protects, lever 96 is rotated causing lever 93 to remove the bias of spring 92 and allow pilot valve 76' to open. Such operation of pilot valve 76' causes opening of balanced pressure valve 90, best shown in Fig. 3, whereupon fluid from source 59 is admitted through passage 91 to force piston 84 upwardly, thereby moving valve member 81 and interconnecting conduits 63 and 15. Rotation of lever 96 also opens tripping valve 106 so that, as soon as valve 104 is opened upon slight movement of piston 84, fluid pressure is admitted to pneumatic tripping means 107, causing rotation of trip finger 116 as well as latch 52 so that trip-free mechanism 37 is released and circuit breaker 10 is opened under the operation of spring means 29 and 30. It will be understood that, since valve member 81 was moved prior to the admission of fluid to pneumatic tripping means 107, a blast of fluid adjacent contacts 11 and 12 is assured before the initiation of the opening movement of circuit breaker 10.

Even though solenoid 95 should be immediately deenergized, cam member 125 will continue to hold pilot valve 76' and consequently blast valve 64 open for a predetermined time, depending upon the cam surface provided on cam 125 so as to time the fluid blast adjacent contacts 11 and 12 and insure interruption of the circuit. The operation of the circuit breaker described thus far would be the same if a manual force were

applied to cable 102 instead of energizing opening solenoid 95.

To close circuit breaker 10, it is necessary to energize closing solenoid 80 through any suitable control circuit, whereupon balanced pressure valve 61 is opened to cause fluid motor 33 to provide the necessary closing force for charging springs 29 and 30 and for closing the contacts of circuit breaker 10. Since fluid motor 33 acts through the trip-free thrust-transmitting linkage 37, circuit breaker 10 may be opened at any time during the closing stroke. Furthermore, cam 125 acting through rods 101 and 101' causes operation of blast valve 64 without effecting tripping valve 106 or pneumatic tripping means 107 so that a blast of fluid is provided adjacent contacts 11 and 12 when the circuit breaker is being closed. Since blast valve 64 is held open by virtue of cam 125 during a portion of the closing stroke, high-speed trip-free operation may be obtained and a continuous supply of gas of circuit breaker 10 under pressure adjacent contacts 11 and 12 will be provided.

It will be apparent to those skilled in the art that my invention is not limited to the particular construction shown but that changes and modifications may be made without departing from the spirit and scope of my invention and I aim in the appended claims to cover all such changes and modifications.

What I claim as new and desire to secure by Letters Patent of the United States, is:

1. In an operating system for an electric circuit breaker comprising a plurality of relatively movable contacts, means for producing relative movement between said contacts to open said circuit breaker, a source of fluid under pressure, a blast valve associated with said source for producing upon opening thereof a blast of fluid past the contacting portions of said contacts for arc-extinguishing purposes during the opening movement of said circuit breaker, pneumatic means for initiating the opening movement of said circuit breaker, and valve means directly controlled by the opening movement of said blast valve for connecting said source and said pneumatic means to initiate the opening movement of said circuit breaker only after a predetermined opening movement of said blast valve.

2. In an operating system for an electric circuit breaker comprising a plurality of relatively movable contacts, means for producing relative movement between said contacts, a source of fluid under pressure, a valve associated with said source for producing a blast of fluid past the contacting portions of said contacts for arc-extinguishing purposes during both opening and closing movements of said circuit breaker, means for opening said valve in response to an abnormal current condition on the power circuit associated with said circuit breaker prior to any opening movement of said circuit breaker, pneumatic means for initiating the opening of said circuit breaker, means directly controlled by the opening movement of said valve for connecting said source and said pneumatic means to initiate the opening movement of said circuit breaker after a predetermined opening movement of said valve, and means for maintaining said valve in the open position until a predetermined separation of said relatively movable contacts has occurred.

3. In an operating system for an electric circuit breaker of the fluid-blast type comprising a plurality of relatively movable contacts, means for producing relative movement between said contacts,

contacts, a source of fluid under pressure, a blast valve associated with said source for producing a blast of fluid past the contacting portions of said contacts for arc-extinguishing purposes during both opening and closing movements of said circuit breaker, a plurality of means for operating said valve prior to any opening movement of said circuit breaker, pneumatic means for initiating the opening movement of said circuit breaker, valve means directly controlled by the opening movement of said blast valve for connecting said source and said pneumatic means to initiate the opening movement of said circuit breaker only after a predetermined opening of said blast valve has occurred, and means responsive to relative movement between said contacts for determining the closing instant of said blast valve.

4. In an operating system for an electric circuit breaker comprising a plurality of relatively movable contacts, means for producing relative movement between said contacts, a source of fluid under pressure, a valve associated with said source for producing a blast of fluid past the contacting portions of said contacts for arc-extinguishing purposes during both opening and closing movements of said circuit breaker, means for opening said valve in response to an abnormal current condition on the power circuit associated with said circuit breaker to produce said blast of fluid past the contacting portions of said contacts prior to any opening movement of said circuit breaker, means for initiating the opening of said circuit breaker after a predetermined opening movement of said valve, and means for maintaining said valve in the open position until a predetermined separation of said relatively movable contacts has occurred, said last-mentioned means being so constructed and arranged to cause opening of said valve at a predetermined point during the closing stroke of said circuit breaker.

5. In an operating system for an electric circuit breaker of the fluid-blast type comprising a plurality of relatively movable contacts, means for producing relative movement between said contacts, a source of fluid under pressure, a valve associated with said source for producing a blast of fluid past the contacting portions of said contacts for arc-extinguishing purposes during both opening and closing movements of said circuit breaker, means for opening said valve in response to an abnormal electrical condition occurring on the power circuit associated with said circuit breaker, manual means for opening said valve, and pneumatic means arranged to be connected to said source directly by the opening movement of said valve for initiating the opening movement of said circuit breaker after a predetermined opening movement of said valve.

6. In an operating system for an electric circuit breaker comprising a plurality of relatively movable contacts, means for producing relative movement between said contacts, latching means for holding said contacts in current-conducting engagement when said circuit breaker is in the closed position, a fluid-operated plunger for releasing said latching means, a source of fluid under pressure, a blast valve associated with said source for producing a blast of fluid past the contacting portions of said contacts for arc-extinguishing purposes during the opening movement of said circuit breaker, and valve means connected to said blast valve and operable after a predetermined opening movement of said blast valve for connecting said source with said fluid-

operated plunger so that release of said latching means and consequent opening of said circuit breaker occur.

7. In an operating system for an electric circuit breaker comprising a plurality of relatively movable contacts, means for producing relative movement between said contacts, means for holding said contacts in current-conducting engagement when said circuit breaker is in the closed position, fluid-operated means for releasing said last-mentioned means so that said first-mentioned means may cause opening movement of said circuit breaker, a source of fluid under pressure, a piston-operated blast valve associated with said source for producing a blast of fluid adjacent said contacts for arc-extinguishing purposes during the opening movement of said circuit breaker, a valve mounted on said piston and arranged to be opened after a predetermined opening movement of said blast valve for interconnecting said source and said fluid-operated means so that opening movement of said circuit breaker may occur only after the existence of a blast of fluid for arc-extinguishing purposes adjacent said contacts.

8. In an operating system for an electric circuit breaker comprising a plurality of relatively movable contacts, a fluid motor for producing relative movement between said contacts, a source of fluid under pressure for operating said motor, means for interconnecting said source of fluid and said motor for closing said circuit breaker, energy-storage means for opening said circuit breaker so constructed and arranged as to be charged during the closing stroke of said circuit breaker, means for restraining said energy-storage means in the charged condition when said circuit breaker is in the closed position, tripping means for releasing said energy-storage means to open said circuit breaker whereby high-speed opening of said circuit breaker is obtained, means including a blast valve for producing a blast of fluid adjacent said contacts for arc-extinguishing purposes during the opening movement of said circuit breaker, and pneumatic means for releasing said tripping means when a predetermined opening movement of said blast valve has occurred.

9. In an operating system for an electric circuit breaker comprising a plurality of relatively movable contacts, means for producing relative movement between said contacts, a trip-free thrust-transmitting mechanism interposed between said last-mentioned means and said relatively movable contacts, means for holding said contacts in current-conducting engagement when said circuit breaker is in the closed position, fluid-operated means for releasing said last-mentioned means so that said first-mentioned means may cause opening movement of said circuit breaker, a source of fluid under pressure, a blast valve associated with said source for producing a blast of fluid past the contacting portions of said contacts for arc-extinguishing purposes during the opening movement of said circuit breaker, and means for operating said fluid-operated means only after a predetermined operation of said blast valve to insure a blast of arc-extinguishing fluid around the contacting portions of said contacts upon separation thereof.

10. In an operating system for an electric circuit breaker comprising a plurality of relatively movable contacts, a fluid motor for producing relative movement between said contacts, a source of fluid under pressure for operating said

motor, valve means for connecting said source of fluid with said fluid motor for closing said circuit breaker, means for opening said circuit breaker, a trip-free thrust-transmitting mechanism interposed between said fluid motor and said relatively movable contacts, means including a blast valve associated with said source for producing a blast of fluid adjacent said contacts for arc-extinguishing purposes upon opening said circuit breaker, means for restraining said trip-free mechanism to hold said circuit breaker in the closed position, and pneumatic means for releasing said last-mentioned means to initiate opening of said circuit breaker only after a predetermined opening movement of said blast valve has occurred.

11. In an operating system for an electric circuit breaker comprising a plurality of relatively movable contacts, means for producing relative movement between said contacts, latching means for holding said contacts in current-conducting engagement when said circuit breaker is in the closed position, fluid-operated means for releasing said last-mentioned means so that said first-mentioned means may cause opening movement of said circuit breaker, a source of fluid under pressure, a blast valve associated with said source for producing upon opening thereof a blast of fluid past the contacting portions of said contacts for arc-extinguishing purposes during the opening movement of said circuit breaker, means for operating said fluid-operated means only after a predetermined opening of said blast valve to insure a blast of arc-extinguishing fluid past the contacting portions of said contacts upon separation thereof, and a mechanical interlock for rendering said fluid-operated means ineffective when the pressure of said source falls below a predetermined value.

12. In an operating system for an electric circuit breaker comprising a plurality of relatively movable contacts, a fluid motor for producing relative movement between said contacts, a source of fluid under pressure for operating said motor, means for interconnecting said source of fluid and said motor for closing said circuit breaker, energy-storage means for opening said circuit breaker so constructed and arranged as to be charged during the closing stroke of said circuit breaker, means for restraining said energy-storage means in the charged condition when said circuit breaker is in the closed position, tripping means for releasing said energy-storage means to open said circuit breaker whereby high-speed opening of said circuit breaker is obtained, a blast valve for producing upon opening thereof a blast of fluid past the contacting portions of said contacts for arc-extinguishing purposes during the opening movement of said circuit breaker, pneumatic means for releasing said tripping means when a predetermined opening movement of said blast valve has occurred, and means for rendering said pneumatic means ineffective when the pressure of said source falls below that required for safe operation of said circuit breaker.

13. In an operating system for an electric circuit breaker comprising a plurality of relatively movable contacts, means for producing relative movement between said contacts, latching means for holding said contacts in current-conducting engagement when said circuit breaker is in the closed position, a fluid-operated plunger for releasing said latching means, a source of fluid under pressure, means for connecting said source

with said fluid-operated plunger to cause release of said latching means and consequent opening of said circuit breaker, and a mechanical interlock for preventing the release of said latching means when the pressure of said source falls below a predetermined value.

14. In an electric circuit breaker of the fluid-blast type comprising a plurality of relatively movable contacts, means for producing relative movement between said contacts, a source of fluid under pressure, valve means associated with said source for producing a blast of fluid adjacent said contacts during both the circuit-interrupting and the circuit-closing operations of

said circuit breaker, means for preventing said first-mentioned means from operating prior to operation of said valve means, means for initiating the operation of said valve means, and mechanical means including a pivoted assembly interposed between said valve means and said means for producing relative movement between said contacts for timing the opening of said valve means during the circuit-interrupting operation, **10** said last-mentioned means being so constructed and arranged to control said valve means so as to produce a fluid blast adjacent said contacts during the circuit-closing operation.

CARL THUMIM.
